DESIGN FOR A COMBINED SPOOL HOLDER AND RULER

Manfred Rosenblatt, Kew Gardens, N. Y.

Application June 7, 1945, Serial No. 119,942

Term of patent 3½ years

(Cl. D3—19)

To all whom it may concern:

Be it known that I, Manfred Rosenblatt, a citizen of the United States of America, residing at Kew Gardens, in the county of Queens and State of New York, have invented a new, original, and ornamental Design for a Combined Spool Holder and Ruler, of which the following is a specification, reference being had to the accompanying drawing, forming part thereof.

The figure on the drawing is a front perspective view of a combined spool holder and ruler showing my new design.

I claim:

The ornamental design for a combined spool holder and ruler, substantially as shown.

MANFRED ROSENBLATT.
